CLAIM

The ornamental design for a display stand for necklaces or the like, substantially as shown and described.

DESCRIPTION

FIG. 1 is a perspective view of a display stand for necklaces or the like showing my new design;

FIG. 2 is a perspective view thereof with the cover member shown in raised position to permit mounting or removal of the necklaces;

FIG. 3 is a top plan view thereof;

FIG. 4 is a side elevational view thereof; and

FIG. 5 is a bottom plan view thereof.

FIG.1
